CONTROL MECHANISM FOR LIQUID
DISPENSING APPARATUSClement P. Griffith, Fort Wayne, Ind., assignor to
S. F. Bowser & Company, Incorporated, Fort
Wayne, Ind., a corporation of Indiana

Application May 17, 1939, Serial No. 274,163

11 Claims. (Cl. 221—95)

This invention relates to a mechanism used to control the operation of a filling station liquid dispensing apparatus. More specifically, the invention relates to a motor control mechanism which is operated to start and stop the dispensing pump as an incident to movements of the dispensing hose as it is removed from or returned to a hose storage device.

One of the objects of the invention is to produce a control mechanism which will start or stop the dispensing apparatus at once upon the initial movement of hose.

Another object of the invention is to produce a control mechanism which will automatically stop the operation of the apparatus when the hose is released.

Still another object of the invention is to provide a control mechanism which will not start the apparatus, regardless of hose movements, until the register has been reset.

Yet another object of the invention is to provide a control mechanism which will yield to undue stresses without breaking.

Yet another object of the invention is to provide a separable hose storage device to which the hose may be readily mounted.

A further object of the invention is to provide a control mechanism which is inexpensive and which can be easily and quickly installed.

Still another object of the invention is to produce a control mechanism, the operation of which is regulated by the reset interlock mechanism.

Other objects will become apparent from a study of the specification in connection with the drawings which are made a part hereof and in which:

Figure 1 is a front elevation, partially broken away, showing one type of concealed hose dispensing apparatus with the control mechanism applied.

Figure 2 is a side elevation of the mechanism of Figure 1 viewed from the right of Figure 1.

Figure 3 is an elevation of the interlocking mechanism with certain parts broken away.

Figure 4 is an enlarged sectional view of the friction mechanism used to actuate the motor switch.

Figure 5 is a perspective view showing the linkage utilized to connect the various elements involved.

Figure 6 is an enlarged view of the upper portion of the linkage shown in Figure 5.

Figure 7 is an end view of the separable hose

reel with the removable flange portion removed.

Referring now to Figure 1, numeral 1 represents a frame to which is attached supporting plates 3 and 5, guide rolls 7 and a housing 9. Plate 3 supports a pump 11, an air separator 13 and a hose reel 15. A motor 17 is belted to pump 11 and is controlled by a switch 19 of any desired vapor proof construction.

The upper plate 5 supports a meter 21 and registers 23, and piping connects the liquid port of the air separator 13 in series with the meter 21, a sight glass 25, and the hose reel 15 which is provided with a spring 16 adapted to rotate the reel and wind up the hose when the operator ceases to pull on the hose. The dispensing hose 21 is connected to the reel at one end and at its other end carries a nozzle 29 of the usual type. The hose is positioned in proper relation to the reel by rolls 7. Figure 7 shows the hose screwed in place in the reel. A portion of the one flange of reel 15 is made removable from the hub of the reel so that access may be had to the hose coupling by which the hose is connected to the fluid passage in the reel hub. The removable flange portion 31 is held in place on the reel by cap screws which are received in threaded holes formed in the reel hub 32.

A bracket 33, shown in Figures 1 and 4, is attached to the reel by screw fastenings which extend through holes 34, and the bracket has fixed centrally therein, a spindle 35. The latter element is provided with a pin 37 adapted to enter a hole in the bracket and to be welded in place therein; a flange 39; a journal portion 41 about which a lever 43 is rotatable; and a reduced threaded stem 45, which is adapted to receive a castellated nut 47. A hole 49 is provided through the stem 45 and is adapted to receive a cotter pin which serves to hold the nut against turning.

One or more friction elements 51 are confined between the lever 43 and a washer 53 which is held in place by nut 47. Adjustment of the nut on stem 45 regulates the amount of drag applied to the lever.

A shaft 55 (Figures 1, 2 and 5) is mounted at its ends for rotation in bearings supported on the frame 1, and has fixed to it two levers, 57 and 59, which rotate with the shaft. A link 61 is provided with ends bent at ninety degrees to its axis, and these ends are received in holes in the levers 43 and 57 respectively. The link may be held in place by any suitable means such as by cotter pins inserted in holes in the bent ends.

A control lever 63 is pivoted at one end on a member 65 fixed to the frame 1, while its other end projects through an opening in the housing 9. An L-shaped lever 67 is pivotally mounted on the projecting end of the lever 63. One arm 69 of lever 67 extends in the direction of lever 63 while the other arm 71 extends upwardly substantially at right angles thereto to cooperate with a fixed lug 73. When the lever 67 is in its farthest clockwise position as shown in Figure 1, the lug 73 and arm 71 are in alignment and prevent counter-clockwise rotation of lever 63; however, when the lever 67 is rotated to its farthest counter-clockwise position, the arm 71 will clear lug 73 and lever 63 may be rotated 15 in a counter-clockwise direction (Figures 1 and 5).

When the nozzle is on the lever 69, the projection 75 which is a part of lever 63 and projects through a slot in lever 69, prevents operation of the nozzle trigger in a well known manner; and also, the lever 67 is prevented from rotating far enough in the counter-clockwise direction to disalign lever 71 and lug 73. The lever 69 thus serves two purposes, namely, to support the nozzle and to provide a control for moving lever 71 into and out of alignment with the lug 73.

An element 77 is pivotally mounted upon the lever 63 adjacent the support member 65, and is provided with a seeker 79 and a cam 81. The seeker is adapted to enter into notches 83 and 85 which are formed in discs 87 and 89 respectively.

The disc 89 is connected to be rotated by the shaft 91 which is rotated in a clockwise direction (Figure 3) by crank 92 while the registers 23 are being reset to zero position before a dispensing operation is begun. Motion is transmitted from disc 89 to disc 87 by means of a spring 93 which has one end attached to a pin 95 in disc 89 and its other end attached to a pin 97 fixed in disc 87. Pin 95 rides in a slot 96 in disc 87 to limit the relative rotation of the discs.

A pawl 99 is pivoted on the fixed member 65 and is adapted to engage the periphery of disc 87 and to engage a notch 101 therein to prevent rotation of the disc in a counter-clockwise direction beyond a predetermined position. The lower end 103 of the pawl is adapted to engage the inclined edge 105 of the cam 81 and to be rotated thereby out of engagement with disc 87 when the cam is raised.

A clevis 107 is pivotally mounted on lever 63 between the elements 67 and 77 and depends therefrom. A sleeve 109 which opens downwardly is screwed into the clevis and held in adjusted position by a lock nut 111.

The sleeve is adapted to slidily receive the upper end of a push rod 113 which is connected to the free end of lever 59 to form a lost motion connection between lever 63 and the connecting linkage described above. A lug 115 is formed on the push rod and a clevis 117 is pivotally mounted on said lug. A switch operating rod 119 is screwed into the clevis 117 and held in place by a nut, and at its lower end is connected to operate the arm 120 of switch 19, herefore described. A spring 121 is fixed with its upper end on the support 65 and its lower end on the upper portion of sleeve 109.

The lug 15 on rod 113 is so placed that it will engage the lower end of sleeve 109 before the upper end of the rod will contact the upper end of the opening in the sleeve.

Operation

In starting the dispensing operation it is necessary to rotate the reset crank to free the control lever for operation. Until the crank is operated, the seeker 79 will ride against the peripheries of discs 87 and 89 and the lever 63 will accordingly be held down.

When the crank 92 and shaft 91 are rotated, both discs will turn in a clockwise direction (Figure 3) until notch 101 engages pawl 99, whereupon disc 87 will be held against reverse motion with notch 83 in alignment with seeker 79. Reverse rotation of the crank and shaft 91 serves to move disc 89 relative to disc 87, increasing the tension of the spring 93, and pin 95 will move to the other end of slot 96 in disc 87, whereupon rotation of disc 89 will be stopped and in the position in which the notch 85 will be in alignment with notch 83 and seeker 79.

Upon removal of the nozzle from lever 69, the latter may be lifted to disengage arm 71 from lug 73, and upon further lifting of the lever 63, the seeker will enter the notches 83 and 85, and the clevis 107 and sleeve 109 will be raised with respect to the rod 113. Spring 121 holds the lever in the raised position.

As the seeker is raised the cam also is raised, and its edge 105 contacts the end 103 of pawl 99 and disengages the pawl from notch 101 to release disc 87, which, under action of spring 93, moves sufficiently to prevent reengagement of notch 101 and pawl 99 upon return of the lever 63 to normal position. This is possible because the notches 83 and 85 are wider than the seeker 79.

The pump is now conditioned for starting the motor and this is accomplished by pulling on the hose against the tension of spring 16. The bracket 33 moves with the reel in a counter-clockwise direction (Figure 1) and frictionally drives the lever 43 in the same direction through the friction arrangement described above. The force exerted upon the lever 43 may be varied by adjusting the castellated nut to vary the pressure of the friction elements.

The movement of the arm 43 is transmitted by link 61 to lever 57 and by shaft 55 and lever 59, all of which rotate in a clockwise direction to transmit an upward thrust to the push rod 113. The movement of the rod 113 is limited by the engagement of the lug 115 with the lower end of the sleeve 109. Since the switch operating rod 119 is connected to lug 115 and to the switch arm 120, the lifting of rods 113 and 119 will rotate arm 120 in a clockwise direction (Figures 1 and 5) and close switch 19 to start the motor.

When the switch is closed the pump 11 will draw gasoline from the supply tank (not shown) and discharge it under pressure into the air separator 13, whence solid liquid will be discharged into the meter 21, sight glass 25, hose 27 and out the nozzle in the usual manner.

Should the tension on the hose be relaxed for any reason, sufficiently to produce appreciable slack in the hose, the spring will rotate the reel to retrieve the slack hose, and at the very first portion of the retrieving movement, the lever 43 will be rotated in a clockwise direction, its associated linkage will be moved in directions opposite to those described in starting the motor, and the switch 19 will be opened to stop the motor.

If this condition of the apparatus, an unreeling movement of the hose will again start the de-

livery. If, however, the levers 63 and 67 have been drawn to their lowermost positions, it will be necessary to reset the registers before dispensing can again take place.

Such resetting is enforced by reason of the fact that as the levers 63 and 67 are moved down, the seeker is withdrawn from the notches 83 and 85 and the disc 87 moves under action of spring 93 to block entrance of the seeker into the notches. Engagement of the seeker with the periphery of the disc thus prevents appreciable lift of lever 63, and consequently of sleeve 109, with the result that the rod 113 cannot be lifted high enough, under action of the friction mechanism, to effect closure of the motor switch 19. Any reeling or unreeling of the hose will thus be ineffective to operate the unit and the relative rotation between the reel and lever 43 of the control linkage will be permitted by the slipping of the friction clutch.

Applicant desires to point out that the initial yielding and retrieving movements of the hose reel, when the control lever has been raised, effect the correlated operation of the motor switch; and the retrieving action is automatic so that if the hose is dropped or released for any reason, the motor and pump will be shut down.

It should also be noted that if, for any reason, the switch 19 should not be operated to stop the motor upon return of the hose to the reel, the operator will be able to positively open the switch by bringing the nozzle support to the nozzle receiving position. This result is attainable because as soon as the lug 115 is engaged by the sleeve 109, there is a positive thrust connection between levers 63 and 67 thru rod 113 to the switch lever 120 in the direction required to open the switch.

The removable sector of the reel is provided to enable a service man to reach the hose connection at the core of the reel. To render this connection accessible it is necessary to remove the two screws which hold the sector in place and to loosen the screw which holds the other end of bracket 33 in place. The bracket and linkage may then be swung down about the latter screw as a pivot and there will then be sufficient room to permit removal of the removable sector. Of course, all three of the screws may be removed if desired but this is not strictly necessary.

It is obvious that various changes may be made in the form, construction and arrangement of parts, and accordingly, applicant does not desire to be limited to the specific construction herein disclosed by way of example; instead, he desires protection falling fairly within the scope of the appended claims.

I claim:

1. In a liquid dispensing apparatus, a liquid flow line terminating in a hose and a nozzle, means for producing a flow of liquid in said line, a hose storing mechanism mounted for movement to yield or retrieve said hose, a control device movable to different positions to start or stop the flow of liquid in said line, means connecting said storing mechanism with said control device to transmit motion thereto as said storing mechanism moves, a nozzle support mounted for movement to and from nozzle supporting position, means, associated with said nozzle support, constructed and arranged to prevent movement of said control device when said support occupies its supporting position, a resettable register, means for resetting said register to zero

indicating position, means to prevent movement of said nozzle support from supporting position and means operable by said resetting means after resetting is completed for withdrawing said preventing means.

2. In a liquid dispensing apparatus, a liquid flow line terminating in a hose and a nozzle, means for producing a flow of liquid in said line, a hose storing mechanism mounted for movement to yield or retrieve said hose, a control device movable to different positions to start or stop the flow of liquid in said line, means connecting said storing mechanism with said control device to transmit motion thereto as said storing mechanism moves, said connecting means comprising a continuously engaged friction clutch.

3. In a liquid dispensing apparatus, a liquid flow line terminating in a hose and nozzle, means for producing a flow of liquid in said line, a hose storing mechanism mounted for movement to yield or retrieve said hose, a control device movable to different positions to start or stop the flow of liquid in said line, means connecting said storing mechanism with said control device to transmit motion thereto as said storing mechanism moves, said connecting means comprising a crank, a friction clutch connected to be continuously driven by said storing mechanism and adapted to transmit motion in either direction of rotation to said crank.

4. In a liquid dispensing apparatus, a register, a liquid flow line terminating in a hose and a nozzle, means for producing a flow of liquid in said line, a hose storing mechanism mounted for movement to yield or retrieve said hose, a control device movable to different positions to start or stop the flow of liquid in said line, means connecting said storing mechanism with said control device to transmit motion thereto as said storing mechanism moves, a nozzle support mounted for movement to and from nozzle supporting position, a register and nozzle support interlocking mechanism associated with said nozzle support to control the operation thereof, and a lost motion connection between said nozzle support and connecting means, so constructed and arranged as to prevent operation of said connecting means when said nozzle support is in nozzle supporting position.

5. In a liquid dispensing apparatus, a liquid flow line terminating in a hose and a nozzle, means for producing a flow of liquid in said line, a hose storing mechanism mounted for movement to yield or retrieve said hose, a control device movable to different positions to start or stop the flow of liquid in said line, means connecting said storing mechanism with said control device to move said device to one or the other of its positions as said storing mechanism moves, a nozzle support mounted for movement to and from nozzle supporting position, a lost motion connection between said connecting means and nozzle support so constructed and arranged as to prevent movement of said control device in a direction to start said flow supplying means when said support is in nozzle supporting position, a resettable register and an interlock mechanism associated with said register and said support to prevent movement of said support from supporting position except when said register has been reset.

6. In a liquid dispensing apparatus, a liquid flow line terminating in a hose and a nozzle, means for producing a flow of liquid in said

line, a hose storing mechanism mounted for movement to yield or retrieve said hose, a control device comprising a nozzle support movable to different positions to start or stop the flow of liquid in said line, means connecting said storing mechanism with said control device to transmit motion thereto as said storing mechanism moves, a resettable register, means for resetting said register to zero position, means for preventing movement of said control device to start the flow of liquid and means operated by said resetting means for rendering said preventing means ineffective, and additional manually operable means for preventing movement of said control device until said nozzle has been removed from said support.

7. In a liquid dispensing apparatus, a liquid flow line terminating in a hose and a nozzle, means for producing a flow of liquid in said line, a hose storing mechanism mounted for movement to yield or retrieve said hose, a control device movable to different positions to start or stop the flow of liquid in said line, means connecting said storing mechanism with said device to transmit motion thereto as said storing mechanism moves, a nozzle support mounted for movement to and from nozzle supporting position, yieldable means for urging said nozzle support toward non-supporting position, latching means adapted to hold said support in nozzle supporting position, and means, associated with said nozzle support, constructed and arranged to prevent operation of said control device when the support occupies said supporting position.

8. In a liquid dispensing apparatus, a liquid flow line terminating in a hose and nozzle, means for producing a flow of liquid in said line, a hose storing reel mounted for movement to yield or retrieve said hose, said reel comprising a liquid passage terminating in a coupling adapted to receive a complementary coupling on said hose, and a pair of retaining flanges, one of said flanges having a detachable sector disposed adjacent said coupling, a bracket mounted on both the fixed and detachable sectors, a crank mounted on said bracket, yieldable friction means for driving said crank, a control device movable to different positions to start and stop the flow of liquid in said line, and motion transmitting connections between said crank and said control device.

9. In a liquid dispensing apparatus, a liquid flow line terminating in a hose and a nozzle, means for producing a flow of liquid in said line, a hose storing mechanism mounted for movement to yield or retrieve said hose, a control device movable to different positions to start or stop the flow of liquid in said line, constantly engaged but yieldable means connecting said storing mechanism with said control device to

transmit motion thereto as said storing mechanism moves to yield and to retrieve said hose, a nozzle support mounted for movement to and from nozzle supporting position, releasable means for locking said support in nozzle supporting position, and a lost motion connection between said connecting means and said nozzle support constructed and arranged to be in a collapsed condition when said support occupies its nozzle supporting position, so as to prevent movement of said control device, relative to said nozzle support, toward flow starting position when said support is locked in nozzle supporting position and to be extended by movement of said nozzle support from its nozzle supporting position.

10. In a liquid dispensing apparatus, a liquid flow line terminating in a hose and a nozzle, means for producing a flow of liquid in said line, a hose storing mechanism mounted for movement to yield or retrieve said hose, a control device movable to different positions to start or stop the flow of liquid in said line, means connecting said storing mechanism with said control device to transmit motion to said device as said storing mechanism moves, a nozzle support mounted for movement to and from nozzle supporting position, and means, associated with said nozzle support, constructed and arranged to prevent operation of said control device when said support occupies its supporting position, and an additional means constructed and arranged to prevent operation of said nozzle support from supporting position, a resettable register and means actuatable as said register is reset for clearing said last named operation preventing means.

11. In a liquid dispensing apparatus, a liquid flow line comprising a hose, a reel for storing said hose comprising a hub having a liquid passage formed therein terminating in a hose coupling disposed adjacent the central portion of the hub, and flanges mounted one at each end of said hub on either side of said coupling, one of said flanges comprising two complementary sectors, one of which is disposed adjacent said coupling, a crank, a support for said crank having two ends, means for mounting one end of said support on said hub comprising a fastening common to said support and the sector which is adjacent said coupling, means for mounting the other end of said support for pivotal movement upon withdrawal of said common fastening, and motion transmitting linkage connected to said crank and normally disposed to obstruct access to said last named sector and adapted to be moved from obstructing position upon pivotal movement of said support.

CLEMENT P. GRIFFITH.
